(57) **CLAIM**

The ornamental design for the aircraft avionics console, as shown and described.

DESCRIPTION

FIG. 1 is a left rear top isometric view of the aircraft avionics console, showing our new design;

FIG. 2 is a top plan view of the aircraft avionics console;

FIG. 3 is a bottom plan view of the aircraft avionics console;

FIG. 4 is a front elevation view of the aircraft avionics console;

FIG. 5 is a left side elevation view of the aircraft avionics console;

FIG. 6 is a back elevation view of the aircraft avionics console; and,

FIG. 7 is a right side elevation view of the aircraft avionics consoles.

The broken lines illustrate portions of the aircraft avionics console that form no part of the claimed design.
